United States Patent Office.

WILLIAM QUAYLE, OF WARSAW, ILLINOIS.

Letters Patent No. 64,704, dated May 14, 1867.

IMPROVED DOOR-HOLDER.

The Schedule referred to in these Letters Patent and making part of the same.

TO ALL WHOM IT MAY CONCERN:

Be it known that I, WILLIAM QUAYLE, of Warsaw, in the county of Hancock, and State of Illinois, have invented a new and improved Door-Holder; and I do hereby declare that the following is a full, clear, and exact description thereof, which will enable others skilled in the art to make and use the same, reference being had to the accompanying drawings, forming part of this specification.

This invention relates to the manner in which a swinging door is made to stand in any desired position when open, and the invention consists in an arrangement by which a rod and an elastic or other roll is pressed downward upon the floor or carpet, and raised or controlled, as will be hereinafter described.

Figure 1 represents a vertical section of the edge of the door through the line *z z* of fig. 2.

Figure 2 is a side elevation of the door, partly in section through the line *x x* of fig. 1.

Figure 3 is a cross-section through the line *y y*, of fig. 1.

Similar letters of reference indicate like parts.

A represents the door; B B' is a double crank, one portion of which, B, extends through the side of the door, by which the device is operated and controlled; C is a vertical rod, which is connected with the inner crank B' by a wire, *d*, of suitable strength; D represents a spiral spring, which surrounds the rod C; E is a dove-tail-shaped piece of metal, attached to the end of the rod C, and to which the roll is attached; F is the roll; G is a metallic chambered plate, in which the crank B' operates; the outer or plate portion is flush with the edge of the door to which it is screwed; H is another chambered plate similar to G, the outer portion of which is flush with the door, to which it is also screwed. The guide-pieces *a a*, which support the slide E, are attached to the inside of the plate H, as seen in fig. 3; *b* is a piece projecting inward from this plate, and through which the rod C passes. The upper end of the spiral spring D bears against this piece *b*, from which it recoils against the slide E, pressing it and the rod C down with a constant pressure. When the crank is turned up, as seen in the drawing, fig. 2, the rod and the roll F are raised from the floor. It will be noticed that the crank is thrown a little back from its centre of motion, and when it is in this position it may be said to be locked, with the roll drawn up. In the other position (shown in fig. 1) the spring is pressing the roll to the floor. The cross-section (fig. 3) shows the shape of the slide E, and the position of the rod C. The central pivot upon which the roll turns is seen at *i*.

I do not confine myself to a revolving roll in this connection. The roll or any elastic substance might be rigidly attached to the slide and the same effect be produced, but if it revolved it would be less injurious to the floor or carpet, for the door might be frequently moved without turning the crank and raising the slide.

Having thus described my invention, what I claim as new, and desire to secure by Letters Patent, is—

Holding a door in any desired position by raising and lowering the rod C and its attachments, substantially as herein shown and described.

WILLIAM QUAYLE.
